UNITED STATES PATENT OFFICE.

GEORGE H. WILLIS, OF DETROIT, MICHIGAN.

COLLAPSIBLE LADDER.

Application filed January 14, 1921. Serial No. 437,227.

To all whom it may concern:

Be it known that I, GEORGE H. WILLIS, a citizen of the United States, residing at Detroit, in the county of Wayne and State of Michigan, have invented new and useful Improvements in Collapsible Ladders, of which the following is a specification.

This invention relates to ladders and an object of the invention is to provide a ladder which is foldable longitudinally, and collapsible laterally to permit it to be stored in a relatively small space and also to adapt it to a form convenient for carrying from one place to another or for handling while in use.

Another object of the invention is to provide a collapsible ladder structure, wherein suitable latch means are provided for holding the foldable sections in extended position and also one to which rungs are attached to the side rails of the ladder by pivoting bolts, the latter being attached to the side rails by metal clips to eliminate weakening of the side rails by extending the rung attaching bolts therethrough, and further to provide re-inforcing caps mounted over the ends of the rungs through which the pivotal bolts extend for re-inforcing the members thereby providing a strong durable ladder of relatively great longevity.

A further object of this invention is to provide in a ladder structure, an auxiliary section for use in connection with one of the hinged sections of the ladder which is longitudinally extensible and is constructed to permit bracing thereof by the braces of the ladder structure proper, which auxiliary section is adapted to lend the ladder for use on stairways, as either a stairway stepladder or scaffold.

Another object of the invention is to provide a supporting base adapted for detachable connection to the side rails or stiles for preventing the accidental slipping of the ladder when in use.

Other objects of the invention will appear in the following detailed description and in the accompanying drawing wherein:

Fig. 1 is a front elevation of the improved ladder.

Fig. 2 is an edge elevation of the improved ladder, showing the hinged sections folded.

Fig. 3 is an edge elevation of the ladder

showing the hinged sections supported to provide a stepladder. 55

Fig. 4 is a front elevation of the ladder in collapsed position.

Fig. 5 is a detail of the manner of connecting the rungs to the stiles.

Fig. 6 is a horizontal section through one of the stiles illustrating the manner of attaching a rung thereto. 60

Fig. 7 is a detailed view of the hinged connection and latch structure embedded in the ladder. 65

Fig. 8 is a detailed perspective of the supporting base showing it attached.

Fig. 9 is a side elevation of the improved ladder having the auxiliary ladder section associated therewith and positioned for use as a stairway stepladder. 70

Fig. 10 is a view similar to Fig. 9 illustrating the ladder for use as a stairway scaffold.

Fig. 11 is a detailed view of the auxiliary 75 ladder section.

Referring more particularly to the drawing the improved ladder comprises the sections 1 and 2 each of which includes stiles 3 and 4 of ordinary construction. Hinged plates 5 are attached to the meeting ends of each of the stiles 3 and 4 of the ladder sections 1 and 2, and these hinged plates or leaves have lateral projections 6 formed on their upper inner edges through which the hinged pintle 7 extends for hinging or pivotally connecting the ladder sections 1 and 2 to permit them to be disposed at oblique angles to each other or in longitudinal alignment with the meeting ends of the stiles of the sections in engagement to provide an ordinary ladder. The hinging of the ladder sections permits the ladder to be used as a stepladder if desired as shown in Fig. 3 of the drawing and when it is thus used, the sections 1 and 2 are held against accidental movement relative to each other by a brace structure 8 which includes bars 9 and 10, one of which is pivoted to each of the ladder sections and each of which is provided with a plurality of longitudinally spaced openings 11 for receiving the attaching bolts 12 for connecting the bars 9 and 10. Nuts 13 are provided upon the bolts 12 for binding the brace bars 9 and 10 in engagement and a suitable substantially 90

U

shaped bracket 14 is carried by the bar 10 and engages over the bar 9 for securely connecting the bars 9 and 10 remote from the bolt 12. When the ladder is used as an ordinary straight ladder or is collapsed, the bars 9 and 10 are swung upon their pivots into collapsed position.

The rungs 15 of the ladder structure have metal re-inforcing caps 16 mounted over their ends through which the attaching bolts 17 extend. The bolts 17 have relatively large flat heads 18 which are held in binding engagement with the edges of the stiles 3 and 4 by metal re-inforcing clips 19. The metal re-inforcing clips 19 extend entirely about the stiles 3 and 4 and are attached thereto by suitable screws 20 and thus no bolts extend through the stiles to weaken them at the points of connection between the rungs 15 and the stiles 3 and 4. The bolts 17 pivotally connect the rungs 15 to the respective stiles enabling the stiles to be moved towards each other for laterally collapsing the ladder structure as shown in Fig. 4 of the drawing 25 to render it easy for handling and storing. When the ladder is laterally collapsed the rungs 15 lie parallel and in edgewise engagement one with the rung next thereto permitting a relatively narrow compact 30 structure which may be easy to handle and which will occupy a minimum amount of space. For the purpose of holding the ladder in extended position as shown in Fig. 1 I provide diagonally arranged brace rods 35 21 which are secured at their ends to the stiles by removable elements such as screws so that certain elements may be removed when collapsing the ladder.

A leaf spring 25 is carried by each of the 40 stiles 3 and 4 of the ladder section 2 and is provided with latch lugs 26 adapted to seat in a recess 27 as shown in Fig. 7 of the drawing to connect the ladder sections 1 and 2 in longitudinal alignment and prevent accidental pivotal movement of one section 45 relative to the other. The ends of the leaf springs 25 adjacent the latch lugs 26 are curved outwardly as shown at 28 to facilitate removal of the lugs 26 from the recess 50 27 when it is desired to fold the ladder sections 1 and 2. If it is so desired a keeper plate 29 may be mounted upon the stiles of the section 1 and perforated to provide an opening which aligns with the recess 27.

A removable base 30 for the ladder structure is provided, which includes sockets 31 adapted to receive the lower ends of the stiles 2 and 3 of the lower section 1 of the ladder and pins 32 are chained to the sockets 31 and are adapted to extend through the upstanding portions of the sockets and through the lower ends of the stiles 2 and 3 to securely connect the supporting baseboard 30 to the ladder structure to prevent

slipping of the ladder and to keep it from 65 tipping when in use.

In Figures 9, 10 and 11 an auxiliary ladder section 40 is illustrated which is provided to permit use of the ladder on steps or stairways, and in Fig. 9 this auxiliary section is 70 arranged to permit use of the ladder as a stepladder on a stairway, while Fig. 10 shows the ladder formed of two auxiliary sections and used as a scaffold. The auxiliary section 40 comprises stiles 41 and 42 to which 75 rungs 43 are connected in the same manner in which the rungs 15 are connected to the stiles 3 and 4. The stiles 41 and 42 carry hinge plates 44 which are adapted to coat with the hinge plates 5 of either of the ladder sections 1 and 2 to pivotally connect the auxiliary section 40 to one of the ladder sections 1 or 2. Side rails or bars 46 are adjustably connected to the stiles 41 and 42 and are held in adjusted positions by the 80 wing nuts 47 which are mounted on bolts 48 that extend through the bars 46 and stiles 41 and 42. By adjustment of the bars 46 relative to the stiles 41 and 42 the length of the auxiliary ladder section 40 may be regulated as desired or as is necessary depending upon the conditions contingent with the use 85 of the ladder.

The auxiliary ladder section 40 is designed to permit the use of the bars 9 and 10 in connection therewith for bracing the ladder structure embodying one of the sections 1 or 2 and the auxiliary section 40. 95

It is, of course, to be understood that the invention may be constructed in various 100 other manners and the parts associated in different relations and, therefore, I do not desire to be limited in any manner except as set forth in the claims hereunto appended.

Having thus described my invention what I claim is:

1. A ladder comprising stiles, metal clips mounted about said stiles at spaced distances, rungs, metal caps mounted about the ends of said rungs, pivoting bolts extending through the metal reinforcing caps, rungs and through one side of said clips, said bolts having relatively large flat heads countersunk in the clips. 110

2. A ladder comprising stiles, metal clips mounted about said stiles at spaced distances, rungs, metal caps mounted about the ends of said rungs, pivoting bolts extending through the metal reinforcing caps, rungs and through one side of said clips, said bolts having relatively large flat heads countersunk in the clips, said ladder composed of two hingedly connected sections, and spring locking means for locking the sections in longitudinal alignment. 115

In testimony whereof I affix my signature.

GEORGE H. WILLIS.
